UNITED STATES PATENT OFFICE.

CALVERT PARKER, OF KEENE, NEW HAMPSHIRE.

BANJO STRUCTURE.

1,422,769.

Specification of Letters Patent. **Patented July 11, 1922.**

Application filed October 30, 1920. Serial No. 420,669.

To all whom it may concern:

Be it known that I, CALVERT PARKER, a citizen of the United States, and a resident of Keene, in the county of Cheshire and 5 State of New Hampshire, have invented a new and Improved Banjo Structure, of which the following is a full, clear, and exact description.

This invention relates to a banjo and has particular reference to a new and improved banjo structure which results in a much improved and richer tone and includes simple adjustable means whereby the quality and volume of the tone may be readily varied at will.

An object of the invention is to provide a banjo structure in which by the provision of a simple and improved arrangement of parts, the tone of the banjo may be improved in quality much above the tone of those now in use.

Another object resides in a particular arrangement and construction of the parts of a banjo which greatly enhances the volume of sound resulting from the playing of the banjo as well as providing a readily adjustable means for the quality of the tone.

A still further object resides in the construction of the rim and sounding board of the banjo so that the sounding chamber between the board and the skin head is made practically moisture proof, thus enabling the head or skin to be kept at the proper tension better than where both surfaces of the head are exposed to the climatic changes.

A still further object resides in the particular construction and arrangement of parts described and claimed hereinafter and shown in the accompanying drawing.

40 In the operation of banjos hitherto known, the sensitiveness of the skin head to climatic changes and the impossibility of readily varying the volume and quality of the tone produced by this actuation has limited the operation of these instruments. My invention provides means whereby a new and improved form of sounding board is built in as an integral part of the rim structure and provided as well with a simple adjusting means whereby both the quality and the volume of the tone of the banjo may be quickly and easily varied.

The invention as illustrated in the drawing of which—

55 Figure 1 represents an inverted plan view of the banjo.

Figure 2 represents a vertical longitudinal section taken on the line 2—2 of Figure 1.

Figure 3 is a transverse vertical section 60 taken on the line 3-3 of Figure 2.

As illustrated in the drawing, the invention is applied to banjos having a neck portion 1 of the usual type. To this is fastened or connected in any well known manner a rim portion 2 which is made up of a plurality of laminated strips of wood 3 suitably fastened together in any well known manner preferably by being glued together. Extending across the rim 2 between the rear of the rim and the neck portion 1 is a dowel post 4.

A skin head 5 of the usual type is stretched across the upper edge of the rim 2 and adjustably clamped thereto by a clamping device comprising a circular ring 6 and adjustable screws 7 which are well known means for tightening the skin head on banjos. 75

In the ordinary type of banjo, the space 80 below the skin head is open, the vibration of the skin head being transmitted through the rim and dowel post to the neck and thus contributing to the vibrating parts which produce the volume of sound. I intend to 85 increase the volume of the sound produced by the playing of this banjo by building into the rim portion a solid sounding board 8 preferably made of any suitable wooden material which extends completely across 90 the opening below the skin head. The upper ends of the laminated rim portion 3 are cut away to provide a flange portion such as 9 upon which the sounding board 8 may rest. The remainder of the rim is 95 then built on top of the ends of the sounding board forming an integral structure. Between the upper face of the sounding board and the lower face of the skin head a stationary toning device 10 is disposed. This 100 toning device extends a suitable distance transversely of the main axis of the banjo and is provided with three points in its upper face such as 11, 12 and 13 which contact and bear against the end side of the skin 105 head and has corresponding contacting surfaces below the above mentioned points in contact with the upper face of the sounding board. The pressure or tension of the skin head is sufficient to keep this toning device 110 in place although it may, if desired, be glued in place. Beneath the sounding

board 8 and extending between the sounding board and the upper face of the dowel post 4 is an adjustable tone regulator 14. This is in the form of a U-shaped member having 5 downwardly extending arms 15 and 16 on opposite sides of the dowel post to hold it in place. It will be readily observed that as the adjustable tone regulator post 14 is moved forward along the dowel post 4 with 10 respect to the stationary toning device 10, the character of the vibration of the sounding board 8 will be varied and thus the volume and quality of the tone produced in the banjo will also be varied. The space beneath the skin head 5 and the sounding board 8 designated by the numeral 17 constitutes a sounding chamber which further enhances the production of the required 15 volume of sound. The usual strings 18 are 20 suitably connected to a tail piece 19 and pass over the usual bridge 20. It will be apparent that the sounding board 8, without departing from the spirit of the invention, can be placed below the dowel post 4.

25 What I claim is:—

1. A banjo comprising a rim, a neck, a dowel post extending from the neck across the rim, a skin head disposed across one face of the rim, a sounding board built into 30 the rim and completely closing the space beneath the skin head, said sounding board lying between the dowel post and the skin head and an adjustable tone regulating device located between the dowel post and the 35 sounding board to control the vibration of the sounding board.
2. A banjo comprising a rim, a dowel

post extending across said rim, a sounding board disposed adjacent the dowel post and adjustable means extending between the sounding board and the dowel post for controlling the vibration of the sounding board. 40

3. A banjo comprising a rim, a skin head stretched across the rim, a dowel post extending across the rim, a sounding board closing the opening beneath the rim and lying between the skin head and the dowel post, a tone regulator disposed between the sounding board and the skin head and an adjustable tone regulator disposed between 45 the sounding board and the dowel post. 50

4. A banjo comprising a rim portion, a skin head stretched across one face of the rim, a sounding board built into the rim and completely closing the space below the 55 skin head, a dowel post extending across the rim on the outside of the sounding board, a tone regulating bar disposed between the skin head and the sounding board, said tone regulating bar extending transversely of the 60 axis of the banjo and having a plurality of points contacting with both the sounding board and the skin head and an adjustable tone regulator disposed between the sounding board and the dowel post. 65

5. A banjo comprising a rim, a sounding board extending across said rim and adapted to vibrate during the operation of the instrument, a dowel post extending across the rim beneath said member, and an adjustable 70 tone-regulating device disposed between the dowel post and said member and bearing against said member.

CALVERT PARKER.
